UNITED STATES PATENT OFFICE.

DONALD C. OVERBAGH, OF CHICAGO, ILLINOIS.

CONNECTOR FOR ARMORED CONDUCTORS.

1,328,290.

Specification of Letters Patent. Patented Jan. 20, 1920.

Application filed October 31, 1918. Serial No. 260,422.

To all whom it may concern:

Be it known that I, DONALD C. OVERBAGH, a citizen of the United States, residing at 3617 Pine Grove avenue, Chicago, in the 5 county of Cook and State of Illinois, have invented a new and useful Improvement in Connectors for Armored Conductors, of which the following is a specification.

My invention relates particularly to connectors for application to outlet-boxes used 10 in electrical installations, for firmly securing the end-portions of the armors for the conductors, relative to the outlet-boxes, the insulated conductors shielded by said armors extending through the connectors into 15 the boxes.

Hitherto, connectors of this character have been so constructed that a single armor-section only could be secured by the 20 connector to the outlet-box, or in other words a pair only of current-conducting wires could be led into an outlet-box through a single connector. Thus when it becomes desirable, as it often does, to provide a plurality of pairs of conductors extending into 25 an outlet-box, as for example where it is desirable to provide for the passage of the current through a plurality of boxes in series and tap the conductors therein for the fixtures adjacent the boxes, to provide two of 30 the connectors secured to such box at different points, each for two wires. This requirement is not only objectionable on account of expense of equipment, but it is often times very inconvenient, if not impracticable, to secure two of the connectors to a single outlet-box, particularly when the 35 second connector is to be attached to the box after the latter has been installed, and especially in the case of re-wiring a building, for example, as often times the portion 40 of the box to which the second connector is to be attached, is covered by a part of the building construction, as for example a joist, 45 or the like.

One of my objects is to overcome the objections above pointed out and to provide a connector which shall have a single point of connection with the outlet-box and serve as 50 the securing means for a plurality of armor portions of conductors, whereby a plurality of sets of current-conducting wires may be let into a box by the employment of a single connector only and another object is to provide improved means for connecting the armor or armors to the body of the connector, 55

whether adapted for receiving two armors or one only, which shall be simple and inexpensive of construction, readily adjusted to clamping position and stable.

60

Referring to the accompanying drawing:

Figure 1 is a sectional view taken at the line 1—1 on Fig. 2 and viewed in the direction of the arrows of an outlet-box equipped with a connector constructed in accordance 65 with my invention and shown in connection with the armored-portions of current-conductors secured thereto, the conductors being represented as extending into the outlet-box. Fig. 2 is a section taken at the line 2—2 on 70 Fig. 1 and viewed in the direction of the arrows; and Fig. 3, an end view of the connector with the conductors removed, this view being taken from the left-hand side of Fig. 1, and the conductors shown by dotted 75 lines.

According to the preferred embodiment of my invention, my improved connector, which is preferably made of malleable iron, though it may be made of any other suitable 80 material, is formed of the hollow crosswise-elongated portion 3 of a length somewhat greater than double the diameter of the armor surrounding the conductors to be secured by the connector, and the restricted 85 hollow portion 4 with the shoulder-portion 5 interposed between the portions 3 and 4. The portion 4 is of an external diameter adapting it to be inserted through the opening usually provided in outlet-boxes for connectors for conductors, and is externally 90 screw-threaded as represented at 6 for engagement with a nut 7; and the portion 3, for receiving the ends of the armors, preferably contains a partly mutilated rib 8 as 95 shown dividing the space therein into two armor-receiving sockets 9.

The portion 3 of the device is provided with means for securing therein the ends of the armors of conductors to be attached to 100 the connector, these means, according to the illustrated embodiment of my invention, comprising machine-screws 10 screwing in openings 11 in a wall 12 of the part 3 which is preferably thickened as indicated, these 105 screws being so located that their inner ends will extend into intersecting tangential position relative to the inner sides of the armors when positioned therein, as shown in Fig. 3.

In the use of the connector for connecting thereto a pair of armor-portions of con-

110

ductors, the ends of the armor-portions 13 thereof extend into the sockets of the portion 3 of the connector and by rotating the screws 10 into engagement at their inner ends with the armors 13 the latter are firmly clamped in position on the connector, the unarmored-portions of the conductors 14 and 15 extending through the opposite, reduced, end-portion 4 of the connector, which 10 is secured to the outlet-box, as for example that illustrated at 16, by inserting its reduced-portion 4 into the connector-opening of the box and thereupon applying the nut 7 to the inner end of the portion 4 as shown 15 in Fig. 1. In this figure, the conductors 14 and 15 are shown spliced together in accordance with common practice, to provide for the wiring thereto of the fixture (not shown), for use in connection with which the 20 outlet-box is provided, and to connect up this box in series with another outlet-box, (not shown).

It will be understood that if desired, the connector illustrated may be used for connecting with an outlet-box a single armor-section, as where the current is not to be carried to another outlet-box, and thus the connector may be used as a connector for one or a plurality of armor-sections and conductors as desired, also, if desired, the connector may be constructed for receiving one armor-section only.

While I have illustrated and described a particular construction in which my invention is embodied, I do not wish to be understood as intending to limit it thereto, as the same may be variously modified and altered without departing from the spirit of my invention.

What I claim as new and desire to secure 40 by Letters Patent is:

1. A connector for armored conductors forming a fitting and formed with a hollow portion at which the connector is adapted to connect with the opening of an outlet-box, 45 and a hollow portion opening into said first referred-to hollow portion, for receiving the ends of a plurality of armor-portions of conductors, and means for securing said armor portions in place to permit the ends 50 of the conductors to extend into said first-referred-to hollow portion, extending into a position between said armor portions and clamping them to the wall of said second-referred to hollow portion. 55

2. A connector for armored conductors forming a fitting and formed of a hollow member having a portion at which the connector is adapted to connect with the opening of an outlet-box and a portion for receiving the ends of a plurality of armor-portions of conductors, opening into said first-named portion, and means for securing said armor portions in place. 60

3. A connector for armored conductors 65 forming a fitting and formed of a hollow member adapted to connect with the opening of an outlet-box and adapted to receive the ends of a plurality of armor-portions of connectors, with a partition arranged to extend between the said armor portions, and screw devices screwing in the wall of said hollow member and adapted to engage at their free inner ends the armor-portions of the conductors tangentially of the latter for 70 clamping the conductors in place against the wall of said hollow member. 75

DONALD C. OVERBAGH.
